United States Patent Office

Des. 210,772
Patented Apr. 16, 1968

210,772

VEHICLE SEAT

Edgar J. Smith, Plankinton, S. Dak. 57308

Filed Oct. 3, 1966, Ser. No. 4,138

Term of patent 7 years

(Cl. D15—8)

FIG 1

FIG 2

FIG 3

FIG 4

FIG 5

FIG 6

FIGURE 1 is a perspective view of a vehicle seat embodying my new design;

FIGURE 2 is a right side elevation view of the vehicle seat; the left side view being a mirror image of the same;

FIGURE 3 is a front elevation view of the same;

FIGURE 4 is a rear elevation view of the same;

FIGURE 5 is a top view of the same; and

FIGURE 6 is a bottom view of the same.

I claim:

The ornamental design for a vehicle seat, as shown and described.
